LOCK DEVICE

Fred Ernest, Gardena, Calif.

Application May 15, 1948, Serial No. 27,178

11 Claims. (Cl. 292—1)

1

The present invention relates to lock devices, and is more particularly directed to lock devices embodying rotary bolts especially designed for use on automobile doors.

In the type of lock device described in United States Patent No. 2,249,018 a rotary bolt cooperates with a keeper and a cam mechanism to hold an automobile door closed. The rotary bolt includes an outer toothed portion engageable with the keeper, and an inner toothed portion cooperable with a spring actuated pivoted cam mechanism for urging and maintaining the door in its locked position. In order to lock the door in closed position, the keeper must rotate the bolt to a sufficient extent, prior to full closing of the door, to displace the cam mechanism to a tripping position, from which the mechanism is operative to close the door fully and maintain it in such condition until purposely opened by a retracting or releasing device. In addition to its function of closing and holding the door closed, the rotary bolt, keeper and spring actuated cam mechanism serve to prevent rattling of the door.

Lock devices of the type referred to operate effectively, so long as the cam mechanism can be shifted to its tripping position prior to full closing movement of the door with respect to the stationary post or pillar of the door opening. Certain conditions oftentimes prevent such shifting movement of the cam mechanism. These include manufacturing errors in the individual parts, the particular design of the parts, their improper assembly with respect to each other, their distortion, wear of the cooperating surfaces from usage, and improper disposition of the parts, ordinarily resulting from usage.

An object of the present invention is to correct deficiencies in the operation of a rotary lock device without the necessity for replacing any of its parts or of dismantling the devices.

Another object of the invention is to provide a simple mechanism for correcting deficiencies in the operation of a rotary lock device, which can be installed very quickly without the need for disturbing any of the parts of the lock device.

Another object of the invention is to insure the proper operation of the rotary lock device through use of an auxiliary mechanism which avoids interference with the free opening and closing movements of a door or similar closure. More particularly, the auxiliary mechanism does not tend to effect binding of the door on its hinges or in the frame defining the door opening.

A further object of the invention is to provide a device for use on a rotary door lock that com-

2

pensates for wear of the parts, their improper relative disposition, and manufacturing errors.

Still another object of the invention is to provide a device for correcting the operation of a rotary lock, without disturbing its parts, in situations wherein the longitudinal distance between the stationary and movable lock parts is too great for proper operation of the lock device.

A further object of the invention is to provide an attachment for correcting the operation of a rotary lock device, which can be installed easily, and which is not susceptible to inadvertent removal or loss.

Another object of the invention is to provide an attachment for the rotary bolt of a lock device, which is capable of installation without removing the cover or housing for the bolt.

This invention possesses many other advantages, and has other objects which may be made more clearly apparent from a consideration of several forms in which it is embodied. These forms are shown in the drawings accompanying and forming part of the present specification, and will now be described in detail, for the purpose of illustrating the general principles of the invention. It is to be understood, however, that this detailed description is not to be taken in a limiting sense, since the scope of the invention is best defined by the appended claims.

Referring to the drawings:

Figure 1 is a somewhat diagrammatic view of a rotary bolt lock device, with the cam mechanism in its tripping position;

Fig. 2 is a view similar to Fig. 1, with the cam mechanism in its locking position;

Fig. 3 is a view similar to Fig. 1, illustrating a defective rotary lock and the inability of the cam mechanism to be disposed in its tripping position;

Fig. 4 is an exploded, isometric view of a rotary bolt and an attachment for the rotary bolt which is capable of insuring movement of the cam mechanism to its tripping position;

Fig. 5 is a diagrammatic view of the manner of installing the attachment disclosed in Fig. 4 on the rotary bolt;

Fig. 6 is a somewhat diagrammatic view of a lock device, with the attachment shown in Fig. 4 fully installed on the rotary bolt;

Fig. 7 is a view similar to Fig. 6 of another embodiment of the invention;

Fig. 8 is a view similar to Fig. 6 of still another form of the invention;

Fig. 9 is a section taken along the line 9—9 on Fig. 8;

Fig. 10 is a partial end elevation of another embodiment of the invention; and

Fig. 11 is a section taken along the line 11—11 on Fig. 10.

The rotary door lock disclosed in the drawings includes a keeper 10 secured to a stationary post or pillar 11 of a vehicle frame in any suitable manner, as by use of screws 12 passing through its plate portion 13 (see Fig. 9). This keeper is adapted to cooperate with a rotary bolt 14, mounted upon the outer end of a door 15 which can swing to and from closed position upon hinges (not shown) in the usual manner. The keeper 10 projects longitudinally from the stationary post 11 and is engageable with the bolt 14, rotatable upon a pin 16 secured between a plate 17, suitably attached to the casing 18 of the lock device within the door, and to the end portion of a housing member 19 partially enclosing the rotary bolt 14 and suitably attached to the casing 18.

The rotary bolt 14 includes an outer keeper cooperating member 20 having a plurality of circumferentially equidistant teeth 21 cooperable with the forward inclined face 22 of the stationary keeper 10, and also with its rear inclined face 23. The forward keeper face 22 is engageable with the rear face 24 of each tooth of the outer portion of the rotary bolt, while the rear inclined keeper face 23 is adapted to be engaged by the forward face 25 of each tooth, for the purpose of holding the door in closed position and without rattling, in cooperation with a stationary abutment 26 extending from the outer end of the door 15 and suitably secured to the door casing 18. The lower surface 27 of this abutment is engageable with the upper surface 28 of the projecting keeper 10.

The complete locking action of the device is dependent upon the action of a cam mechanism. This mechanism includes a plurality of longitudinally spaced holding cams or pawls 29 pivotally mounted on a pin 30 extending between and secured to the outward projecting abutment member 26 and the supplementary plate 17 attached to the casing 18. These pawls 29 are each biased towards an inner toothed portion 31 of the rotary bolt 14, the foot portions 32 of the cams being engageable with the inner teeth 33 in order to hold the rotary bolt in its locking position. A dividing flange or fin 34 separates the outer and inner portions of the bolt, this fin being disposed within a suitable opening 35 in the casing 18.

The cams 29 are biased toward the inner portion 31 of the bolt by individual coil springs 36 bearing against them and suitably anchored to the casing 18. The springs urge the foot portions 32 into the space between adjacent teeth 33, and engage a cam foot with the rear face 37 of one tooth and the forward face 38 of the next tooth, in this manner preventing rotation of the bolt 14 in one direction. The forward face 38 of each tooth is adapted to shift the cams 29 outwardly against the force of their springs 36 upon rotation of the bolt on the pin 16 in the proper direction.

The mechanism described is well known. Further details are unnecessary to an understanding of the present invention, and may be found in United States Patent No. 2,249,018, referred to above.

In the operation of the lock device, as exemplified in the drawings, the door 15 is swung on its hinges toward the post or pillar 11. The upper abutment 26 and the lower bolt 14 on the

door swing toward locking position upon movement to the right, as seen in Figs. 1, 2 and 3. As the door approaches the pillar 11, the cams 29 may be disposed with their foot portions 32 in the locked position in the space between adjacent inner teeth 33. The rear face 24 of a tooth on the outer bolt portion 20 first engages a safety catch 39, forming part of the keeper 10, and pivotally mounted on a pin 40 fixed to the plate 13. A spring 41 normally biases the safety catch 39 in an outward direction, but permits it to swing in a clockwise direction within a keeper opening 42 (as seen in Fig. 1). Outward swinging of the catch 39 is limited by its engagement with the forward side 43 of the keeper, in order to cooperate with the rotary bolt teeth 21 and prevent inadvertent outward swinging of the door 15.

Continued movement of the door towards the fully closed position engages the rear face 24 of a tooth with the forward inclined face 22 of the keeper, causing the bolt 14 to rotate in a counter-clockwise direction on its pin 16, as seen in the drawings. This counter-clockwise rotation causes the forward face 38 of an inner tooth 33 to shift the cams 29 outwardly against the force of the springs 36. Continued movement of the door towards its closed position eventually places the heel 32a of the cams at the outer end of the tooth 33, and a slight rotation of the bolt beyond that position of its tooth 33 would cause the cams 29 to move inwardly within the next space between adjacent inner teeth 33 (Fig. 2), the cam foot 32 engaging the rear surface 37 of the inner tooth 33 and causing further rotation of the bolt 14 under the influence of the springs 36 in a counter-clockwise direction. As the bolt rotates in this manner, the forward face 25, of one of its outer teeth 21 is brought into engagement with the rear inclined face 23 of the keeper 10, causing the tooth to roll upon this rear inclined face, to the right, and moving the door 15 inwardly to fully closed position. In addition, the upward component of thrust between the outer tooth 21 and the keeper surface 23 tends to shift the door downwardly with respect to the keeper, bringing the upper abutment 26 against the upper surface 28 of the keeper. This latter action prevents the door from rattling.

The lock position just described is illustrated diagrammatically in Fig. 2, in which it is apparent that the door 15 cannot open of its own accord, since such action would tend to rotate the bolt 14 in a clockwise direction, the motion being transmitted to the inner cams 29 along a line approximately intersecting the cam pivot pin 30, or to the right thereof, as seen in Fig. 2. As a result, the cams 29 cannot be swung outwardly against the force of their spring 36, which would release the lock and permit opening of the door.

When the door is to be opened, a suitable retracting member 44 is moved downwardly against an arm 45 projecting from one of the cams or pawls 29, which will rock all of the cams against the force of the springs 36 out of engagement with the inner teeth 33, permitting the rotary bolt to rotate freely in both directions, and allowing the door to be opened. During such opening movement, the bolt 14 is first rotated in a clockwise direction by the rear inclined face 23 of the keeper, and may then be rotated further in a clockwise direction by engagement of an outer tooth 21 with the safety catch 39.

It is apparent from the foregoing description that the rotary lock is only effective to perform

its function of securely holding the door in closed position, if the cams 29 can be moved to their tripping position during the closing movement of the door 15, before the door has been fully closed. As disclosed in Fig. 3, the parts are so related as to prevent the inner teeth 33 from so shifting the cams when the door has been moved inwardly to its fullest extent. This is due to the fact that the bolt 14 has not been turned sufficiently on its axis upon full closing of the door, a condition which may be due to a variety of factors. As an example, wear on a keeper tooth 21 may be such that its angular movement upon engaging the keeper 10, is insufficient to place the cams 29 in the tripping position. In addition, sagging of the door 15 might lower the axis of the bolt 14 to such an extent that the keeper 10 engages the teeth 21 at too great a distance from the bolt axis, and, therefore, gives the bolt insufficient angular movement. Another condition encountered is related to the tapering or outward convergence of the outer surface of the keeper 10. If the keeper 10 does not extend longitudinally into the space between the abutment 26 and rotary bolt 14, it will engage the outer teeth 21 of the bolt at too great a distance from its axis to insure sufficient angular movement of the bolt. Other conditions than those specifically mentioned may interfere with appropriate operation of the rotary lock device.

In the form of invention disclosed in Figs. 4, 5 and 6, the foregoing defects are remedied. A clip 46, which may be made of spring steel, is shaped in star fashion generally to conform to the outer toothed portion 20 of the bolt 14. This clip 46 is adapted to fit around the toothed member 20 and is also designed for installation on the latter without the necessity for disturbing any parts of the lock device. It is shaped to have its outer toothed portions 47 of substantially the same face width as the teeth 21 on the outer bolt portion. However, the parts 48 of the clip that are to be disposed in the spaces between adjacent teeth 21 at its root circle are weakened, as by relieving their opposite side edges 49. Such relief may be provided by forming recesses or notches 50 in the side edges of generally arcuate form, as disclosed in Fig. 4.

The spring clip 46 is split to facilitate its installation on the outer portion 20 of the rotary bolt, in the manner described below, the split 51 being so devised as to lie adjacent the root circle within the space between adjacent teeth 21 when installed on the bolt 14. Since the trailing faces 24 of the outer teeth may be longer than the leading faces 25, the spring clip is shaped accordingly, with the portions 52, 53 on opposite sides of its split 51 being of unequal lengths, so that one part 52 will be disposed along the short face 25, and the other part 53 along the long face 24 of adjacent teeth.

The star or lobe-shaped clip 46 can be installed upon the corresponding star wheel 20 of the rotary bolt 14 by expanding the clip, and by hooking the tooth 47 defined on one side by the short end portion 52 over one of the keeper teeth 21, with the short portion 52 disposed along the forward face 25 of the keeper tooth (as in Fig. 5). The clip 46 is opened sufficiently so that its remaining portion is disposed partly around the star wheel 20 and about part of the cover 19 partially enclosing the bolt 14. Such expanding or opening of the spring clip is facilitated and permitted by the weakened sections 48 at its root portions, which allow wide separation between the split ends of the clip without ma-

terially disturbing the toothed form 47 at the outer ends of the clip. After the short portion 52 of the clip has been disposed on one of the teeth 21, the bolt 14 is rotated in a counter-clockwise direction, as seen in Fig. 5, and the clip is fed and placed around the entire outer toothed portion 20 of the bolt, with the opposed ends 52, 53 closely adjacent one another and disposed at the root circle in the clearance space between adjoining teeth 21. The gap 54 between the ends of the clip is preferably placed at the lower portion of the forward face 25 of the tooth, since such portion ordinarily does not engage the keeper 10.

The short leg 52 of the clip is preferably curved upwardly at its end 54 to a slight extent, so as to avoid digging into the face 25 of the keeper tooth 21. The long portion 53 of the clip is so shaped as to cause its end 55 to move inwardly of the adjacent rear toothed face. This end 55 may have a knife-edge so as actually to penetrate the tooth face 24 slightly, and thereby prevent inadvertent movement or removal of the clip from the outer portion 20 of the rotary bolt.

When fully installed on the outer star wheel 20, the clip 46 increases the size of the teeth 21 to an extent insuring proper operation of the rotary bolt lock device. As disclosed in Fig. 3, the rotary bolt is incapable of shifting the cams 29 to their tripping position. The installation of the star-shaped spring clip 46 on the keeper engaging portion 20 of the rotary bolt 14 causes the bolt to be rotated by the keeper 10 at an earlier point in the swinging movement of the door 15 toward closed position, and, therefore, causes the inner teeth 33 to be rotated sufficiently, prior to full closing of the door, as to place the cams 29 in their tripping position, from which they will be biased automatically by their springs 36 towards their holding position illustrated in Fig. 2, which automatically moves the door 15 to fully closed position.

Not only is assurance had that the spring clip 46 on the rotary bolt member 20 will produce sufficient rotation of the latter, but during movement of the bolt 14 by the cams 29 to fully locked position, the spring clip toothed element 46 will engage the rear inclined face 23 of the keeper 10 at an earlier point in its rotation, and insure a snug engagement between the keeper 10, and the forward face of the clip tooth 47, which will prevent rattling of the door.

It is apparent that the tooth-shaped clip 46 will insure proper operation of the rotary lock device, without the necessity for shifting the door 15 with respect to the stationary post or pillar 11, and without the necessity for binding the door upon its hinges. The axis of the rotary bolt 14 may remain the same with respect to the keeper 10 as before the spring clip 46 was added.

The clip insures that the door will be held tightly in closed position without rattling. It can be mounted easily upon the outer toothed member 20 of the bolt without disturbing any parts of the lock. In addition, its weakened sections 48 not only permit opening of the clip, to facilitate its installation on the toothed wheel 20, but the arcuate notches or recesses 50 enable the clip to have substantially the full face width of the teeth 21.

The tooth-shaped clip 46 also prevents the keeper 10, which is usually tapered, from bearing upon small or localized areas on the rotary bolt 14, which is ordinarily made of soft material, such as a zinc alloy. In the absence of the clip 46, this localized bearing area results in the imposition of a high unit pressure on the compara-

tively soft rotary bolt, and accelerates its wear to the point of inoperativeness of the lock mechanism. The hardened steel clip 46, when mounted on the rotary bolt 14, becomes the element engaged by the tapered keeper 10. Because of its physical properties, the clip is highly resistant to wear, insuring continued proper operation of the lock mechanism. In addition, its intervention between the keeper and bolt 14 causes it to distribute the load imposed upon it over a relatively large area of the bolt, thereby decreasing the unit pressure of the latter and insuring its long life.

There is usually a fillet or radius 57 between the dividing fin 34 of the bolt and the inner portion of the teeth 21. This curved fillet 57 would prevent proper insertion of the clip 46 on the toothed member to the full extent desired. The relief portions 50, however, permit the fillets 57 to be received within them, and allow the clip to be placed fully upon the bolt and against the dividing fin or flange 34. It is also to be noted that the provision of the notches 50 on both sides of the spring clip not only weakens the clip at the desired points, but it also allows the same clip to be used on right hand and left hand door locking devices, with assurance that the reliefs 50 will avoid interference with the fillets 57 of the rotary bolts.

The operation of the rotary bolt can be corrected by a different attachment, which may assume the form disclosed in Fig. 7. This attachment comprises a spring-like clip 58, which is placed around the keeper 10, and is shaped to conform to the outer surface of the keeper. Thus, the spring clip 58 includes a depending forward end 59 snugly embracing the forward face 43 of the keeper and a top portion 60 that may be bowed upwardly to a slight extent for engagement with the abutment 26 and assist in holding the door against rattling. The rear portion 61 of the clip is bent downwardly along the rear face 62 of the keeper and also along its rear and forward inclined faces 23, 22. From the forward inclined face 22, the keeper is provided with a hook 63 fitting around the forward margin 64 of the keeper defining the opening 42 in which the safety catch 39 swings. It is apparent that the hook 63 aids in holding the clip securely upon the keeper 10.

The added thickness of material upon the lower inclined faces 22, 23 of the keeper causes a tooth 21 of the rotary bolt to engage the forward inclined portion 65 of the spring clip at an earlier point in the movement of the door 15 to closed position. As a result, the bolt 14 is rotated a greater angular distance during closing of the door, which insures shifting by the inner cam teeth 33 of the cams 29 to their tripping position before the door is fully closed. This tripping position is illustrated in Fig. 7, from which it is apparent that a further slight closing movement of the door 15 will advance the bolt member 14 by a slight amount, to cause the springs 36 to shift the cams 29 down into the tooth space between adjacent teeth 33, or to the position shown in Fig. 2. The door is thus held in snugly closed position, with the forward face 25 of a keeper tooth bearing upon the rear inclined portion 66 of the clip, and with the top 60 of the clip bearing snugly against the abutment 26.

The provision of the forward inclined clip portion 65 not only advances the rotation of the bolt 14, and insures operation of the cams 29 beyond their tripping position, but it also causes the forward face 25 of a keeper tooth to engage the

rear inclined portion 66 of the clip and bear snugly thereagainst to hold the door against rattling movement. The absence of this rear part 66 of the clip might not have caused engagement between the tooth 21 and the keeper 10 proper, in view of wear that might have occurred on either the keeper 10 or tooth 21, or both.

There is yet another important function to the provision of the spring clip 58 disclosed in Fig. 7. The keepers 10 are ordinarily provided with a draft angle or are tapered so as to converge in a direction toward the end of the door 15 (see Fig. 9). This draft angle introduces certain deficiencies into the lock mechanism. For example, should the distance between the door post 11 and the outer end of the door 15 be too great, the keeper might project only slightly into the path of the keeper teeth 21. In view of the convergent taper 67, the teeth 21 would engage the keeper at too late a point in the movement of the door to closed position, and might not result in sufficient rotation of the bolt 14 and shifting of the cams 29 beyond their tripping position. The spring clip 58 overcomes this defect since it is disposed around the keeper 10 with its surfaces substantially parallel to the axis of the bolt 14. That is to say, the draft angle is eliminated and the keeper 10, in effect, is provided with straight top and bottom surfaces. During closing movement of the door 15, a tooth 21 on the rotary bolt would engage the spring clip 58 at an earlier point than heretofore, which will insure rotation of the bolt 14 beyond its cam tripping position.

The defect noted above in connection with the draft angle on the keeper can be overcome by another form of clip, which may assume the shape of a cap 68 adapted to fit completely around the keeper 10, with an opening 69 registering with the keeper opening 42 in which the safety catch 39 moves (Figs. 8 and 9). The side portions or side wall 70 of the cap conform generally to the corresponding surfaces of the keeper 10, and the cap also has an end wall 71 integral with its side wall. The cap finds particular use in conditions wherein the keeper 10 may not project sufficiently into the path of movement of the keeper teeth 21 on the rotary bolt 14, as pointed out in connection with the embodiment of the invention shown in Fig. 7.

As disclosed in Fig. 9, the end of the keeper 10 projects only partly into the path of the keeper teeth 21. The cap 68 has a force fit on the keeper, and need be driven over it only to the extent necessary to insure an adequate projection of the cap into the path of the keeper teeth 21, and to avoid interference with the end of the door 15. The cap need not be driven fully onto the keeper, since its force fit will hold it in appropriately assembled position.

It is evident that the lower inclined portions 72, 73 of the cap will cooperate with the keeper teeth 21 to insure rotation of the bolt 14 to its cam tripping position, and also the exertion of a force by the forward face 25 of a keeper tooth against the rear inclined portion 73 of the cap, to prevent rattling of the door. This last-mentioned function will occur in conjunction with the upper part 74 of the cap engaging the underside of the abutment member 26.

The cap 68 insures appropriate projection of a relatively stationary element into the path of the keeper teeth 21, without the necessity for modifying the relationship between any of the parts of the lock mechanism. As an example, shims need not be placed between the plate 13

and the frame pillar 11, which might produce a similar result, although not to the same extent as the cap, since the latter causes rotation of the bolt at an earlier point in the swinging movement of the door 15 to closed position, than would be the case with engagement of the keeper 10 itself with the outer teeth 21 of the bolt 14.

Proper operation of the lock mechanism may be obtained by another form of cap device 80, of the character disclosed in Figs. 10 and 11. 10 This cap device is similar to the one shown in Figs. 8 and 9, being of generally cup shape, and having an opening 81 to permit appropriate operation of the safety catch 39. The cap, however, need not have a driving fit on the keeper 10, but is made with its side wall 82 straight or parallel to the axis of the rotary bolt 14, or perpendicular to the plate portion 13 of the keeper.

The cap 80 is inserted on the keeper with a snug, but not necessarily a tight, fit. It is held in place by a screw 83, such as a self-tapping screw, extending through the end wall 84 of the cap and threaded into the end wall 85 of the keeper. The extent of outward projection of the cap beyond the end 84 of the keeper can be determined by interposing shims 85 between the end walls 84, 85. It is apparent that tightening of the screw 83 will clamp the shims 85 between the end walls and hold the parts in appropriately assembled relation.

As stated above, the side wall 82 of the cap is straight, and not tapered, which will insure its line or surface contact with the keeper teeth 21 of the rotary bolt 14 along substantially the entire width of the teeth. The tapered keeper 10, or tapered cap 68 (Figs. 8 and 9) would impose only a point bearing contact and would accelerate wear on the rotary bolt 14. The cap 80, therefore, not only advances the rotation of the bolt 14 upon movement of the door to closed position, but it also distributes the load over a greater surface on the bolt teeth 21, which are made of zinc alloy, or other comparatively soft metal, lengthening the life of the rotary bolt 14 and insuring proper operation of the mechanism over greatly extended periods.

In all forms of the invention disclosed, it is unnecessary to modify the relationship between any of the parts of the lock mechanism. It is only necessary to add an auxiliary member or attachment, which is readily mounted upon the parts, and which insures the advance of the bolt rotation to the required extent in obtaining actuation of the cams 29 beyond their tripping positions.

The inventor claims:

1. In a latch mechanism having a toothed rotary bolt member, an abutment spaced from the member, and a keeper member adapted to be received between the bolt member and the abutment for rotating the bolt member into latching engagement with the keeper; said abutment guiding the relative movement of the members; means adapted for mounting upon the toothed portion of said bolt member and engageable with said keeper member for advancing the point at which said keeper member commences rotation of said bolt member upon relative bodily movement of said members toward each other.

2. In a latch mechanism having a keeper member and a rotary bolt member provided with substantially equiangularly spaced transverse teeth: a member conformable to the contour of said bolt member and adapted to lie upon the faces 75

of its teeth for engagement with said keeper member.

3. In a latch mechanism having a keeper member and a rotary bolt member provided with substantially equiangularly spaced transverse teeth: a split member conformable to the contour of said bolt member and adapted to lie upon the faces of its teeth for engagement with said keeper member, the split of said member being adapted to lie in the space between teeth on said bolt member adjacent the base portions of said teeth.

4. A star-shaped clip formed of a thin strip bent to conform to the peripheral contour of the teeth of a toothed rotary bolt member of a latch mechanism.

5. A star-shaped clip formed of a thin strip bent to conform to the peripheral contour of the teeth of a toothed rotary member of a latch mechanism, said clip being split at a trough portion located between adjacent clip projections.

6. A star-shaped clip formed of a thin strip bent to conform to the peripheral contour of the teeth of a toothed rotary bolt member of a latch mechanism, said clip having weakened sections between its generally radial projections.

7. A star-shaped clip formed of a thin strip bent to conform to the peripheral contour of the teeth of a toothed rotary bolt member of a latch mechanism, said clip having weakened sections at its trough portions between its generally radial projecting portions.

8. A star-shaped clip formed of a thin strip bent to conform to the peripheral contour of the teeth of a toothed rotary bolt member of a latch mechanism, said clip having notches in one of its sides at its trough portions between its generally radial projecting portions.

9. A star-shaped clip formed of a thin strip bent to conform to the peripheral contour of the teeth of a toothed rotary bolt member of a latch mechanism, said clip having notches in both of its side margins at its trough portions between its generally radial projecting portions.

10. A star-shaped clip formed of a thin strip bent to conform to the peripheral contour of the teeth of a toothed rotary bolt member of a latch mechanism, said clip having notches in one of its sides at its trough portions between its generally radial projecting portions, said clip being split at one of its trough portions.

11. A star-shaped clip formed of a thin strip bent to conform to the peripheral contour of the teeth of a toothed rotary bolt member of a latch mechanism, said clip having notches in both of its side margins at its trough portions between two generally radial projecting portions, said clip being split at one of its trough portions with an end of said clip defining said split having an inwardly directed sharp edge.
